UNITED STATES PATENT OFFICE.

GEORGE J. NETH, OF DAYTON, OHIO, ASSIGNEE TO THE EGRY REGISTER COMPANY, OF DAYTON, OHIO, A CORPORATION OF OHIO.

AUTOGRAPHIC REGISTER.

Application filed October 6, 1922. Serial No. 592,712.

To all whom it may concern:

Be it known that I, GEORGE J. NETH, a citizen of the United States, residing at Dayton, in the county of Montgomery and State of Ohio, have invented certain new and useful Improvements in Autographic Registers, of which the following is a specification, reference being had therein to the accompanying drawing.

10 My invention relates to autograph registers and in particular to a record roll mechanism.

It is an object to provide positive means in an autograph register for taking up a record roll and maintaining a uniform tension on the record roll strip.

It is a further object to provide means of adjusting this tension at any predetermined point, and of so arranging the mechanism 20 of my invention that it will automatically adjust itself to maintain this tension.

It is a further object of my invention to provide means of driving the record roll and simultaneously actuating the record roll strip, and the issued slips from the issue strips, so that no slack will be permitted in the record roll strip.

It is further object to provide mechanism that, when it rests, will not permit the record roll to become loosened or unwound.

Referring to the drawings:

Fig. 1 is a plan view of a register showing my invention with a portion of the cover broken away to disclose one margin of the 35 perforated paper;

Fig. 2 is a section taken substantially on the line 2—2 of Fig. 1 looking in the directions of the arrow;

Fig. 3 is a section on the line 3—3 of Fig. 2 looking in the direction of the arrow;

Fig. 4 is an enlarged view from the adjusting side of the clutch mechanism;

Fig. 5 is an end elevation of a clutch disassembled;

Fig. 6 is an end elevation of the nut used in the clutch;

Fig. 7 is an end elevation of a nut washer used in the clutch;

Fig. 8 is a section on the line 8—8 of Fig. 4 showing the clutch members, gears, etc. in assembled position.

Referring to the drawings it will be understood that this register is of that type known as a pin wheel register, and that

type in which the pins fit into the holes of 55 the paper as snugly as possible allowing the least amount of play between the pins and the sheets that is feasible for the introduction of the pins in the holes in the margins of the paper.

1 is a cover of a register having a base 2 and a front end wall 3. Beneath the cover is a writing table 4 provided with a slot or slots one on either side for the passage of pins 5 through this slot which is 65 designated 6.

Adjacent to the cover 1 and somewhat beneath it is a cover portion 7 which has a sharp dividing member and elevating member 8.

The cover 1 provides its front edge adjacent to 8 with a cutting edge 9. The cover 1 and the cutting edge 9 are rigid when in operative position.

The pins 5 are mounted on a wheel 10 75 which in turn is mounted on a main driving shaft 11. This shaft is driven by the handle 12 upon which is mounted a movable stop 13 and stop handle 14 of any conventional character. 13 comes in contact 80 with a lug 15 to hold the mechanism at rest.

It will be apparent that there is a space 12² between the ends of 4 and 8. Through this space the record roll strip 16 passes.

The other strips are ejected through the openings between 8 and 9 having been separated by 8 from 16. These strips are designated 17.

Mounted upon the shaft 11 is a master 90 driving gear 18 which meshes with a clutch driving gear 19. The clutch driving gear 19 is loosely mounted upon a sleeve 20 having a flange 21 in the shape of a disk, and an extended portion 22 with threads 23 95 thereon.

20 is supported upon a stub shaft 24 which is screwed into the side wall 25 of the register as at 26. It has a head 27 with a groove 28 for ready engagement with a 100 screw driver. 22 has a cutaway portion 29 cut in the outer end thereof in which the lugs 30 of the lock washer 31 fits to prevent the rotation of the washer.

Another gear similar to 19 designated 105 32 is loosely mounted upon 20, and separated from 19 by a clutch disk fibre designated 33 also mounted loosely upon 20. A

second clutch disk designated 34 of fibre is mounted on the other side of 32 loosely upon 20.

Mounted upon the threaded outer end of 5 20, at 22 is the spring clutch member 35 having a plurality of spring fingers 36, a portion of which as at 37 comes in contact with the face 34, and the remainder of which as at 38 is arched to separate the remainder 10 of them from 34, and to bring the central portion of these fingers where they are united to one another in contact with the locking nut 39 which has a plurality of teeth 40 and grooves 41 therebetween on the periphery thereof.

This nut is threaded upon 22. The lock washer 31 is provided with downturned lugs 43 which are inserted in the grooves or cutaway portions 41 of the nut 39. A locking pin 44 is inserted into the nut and also into the slip clamping member. A similar locking pin 45 is inserted into 34 and is carried by the outer end 37 of 36.

46 is an intermediate gear meshing with 25 the driven gear 32 of the clutch. 46 is pivoted on 47 which is in turn supported by the side wall 25. Meshing with 46 is another pinion 48 turning on 49. 48 meshes with a record roll gear 50 fastened to a record roll 51 which is mounted upon a record roll axle 52 journaled at 53 in the side wall 25. It is likewise supported at the other end by the side wall.

It will be apparent in operation that as 35 the pins 5 engage snugly with holes 54 in the paper the paper will be driven forward, a portion of which is projected and another portion wound on the record roll 51.

As the pins are carried by the wheels 10, 40 there being a wheel on either side of the register engaging with the marginal perforations on either side of the paper, the gears in the gear train will take up the paper strip 16 on the record roll 51 and 45 maintain it taut so that there will be no slack, and the paper will be tightly wound, but in view of the fact that the more paper there is wound upon 51 the greater the tension there will be upon 16 the paper might be torn, or if it were a machine without pin 50 wheels the paper might slip out of alignment through the feeding devices. To relieve this condition the clutch interposed in the driving line when the tension becomes greater than 55 the frictional resistance between the several clutch members, will permit the several members to slip with respect to one another thus adjusting the tension on the strip 16 and maintaining it at a constant value.

60 It will be understood that the parts carried by 20 turn with it as a unit upon 24

until the resistance becomes such that there is a relative movement between 19 and 32.

Accordingly by adjusting the tension on the spring member 36 the clutch action 65 can be modified. When the handle is in a position as shown in Fig. 1 the whole structure including the sheets will be held in a predetermined position during the writing operation upon the sheets 17 and 16 through 70 an opening 55 in the cover 1.

It will be understood that I do not desire to be confined to this specific adaptation of my invention, but comprehend within it suitable modifications which may be necessary in adapting it to varying conditions.

Having thus fully described my invention, what I claim as new and desire to secure by Letters Patent, is:—

1. In an autographic register, a clutch consisting of driving and driven gears and clutch plates on opposite sides of the gears, means to support said gears and clutch plates in cooperative relation, means to maintain said gears and clutch plates in engagement with one another until a predetermined force is applied when they are adapted to slip upon one another including a yielding member mounted on one side of said clutch, an adjustable nut to regulate the compression on said yielding member, means on said nut to positively engage said yielding member to prevent rotation of the latter, means on the yielding means to in turn positively engage with one of the clutch plates, and means to position and lock said nut in adjusted positions.

2. In an autographic register, a clutch consisting of a sleeve having a disk flange on one end, a plurality of spaced gears loosely mounted on said sleeve, at least one clutch disk interposed between said gears on said sleeve, a clutch disk on said sleeve beyond said gears, a yielding member mounted on the other end of said sleeve and having spring arms radiating therefrom engaging with the second mentioned disk to press one of said gears against said flange on the sleeve, a locking nut adjustably threaded on the other end of said sleeve for engagement with said yielding member to regulate its tension, a lock washer having means thereon for positively engaging in cutaway portions in said other end of the sleeve, means on the washer for positively engaging in cutaway portions in the periphery of the nut, a locking pin between the nut and yielding member, and a locking pin between the yielding member and said second mentioned clutch disk.

In testimony whereof, I affix my signature.
GEORGE J. NETH,
